UNITED STATES PATENT OFFICE.

GEORGE C. ZELLER, OF POMONA, CALIFORNIA.

ILLUMINATED HOUSE NUMBER.

Application filed August 3, 1928. Serial No. 297,167.

This invention relates to illuminated numbers, and aims to provide a novel form of number holder which may be positioned in a window of a lighted room so that persons passing 5 in proximity thereto may readily and easily determine the number of the house.

An important object of the invention is to provide a holder of this type wherein the number plates are interchangeable to the end 10 that the numbers may be changed or reversed to meet various requirements, and the number plates removed and replaced by letter plates so that certain reading matter may be presented to view.

15 A further object of the invention is to provide a strip of flexible frosted celluloid as a backing for the number plates so that the outlines of the numbers will be clearly brought out when light rays pass there- 20 through.

With the foregoing and other objects in view which will appear as the description proceeds, the invention resides in the combination and arrangement of parts and in the 25 details of construction hereinafter described and claimed, it being understood that changes in the precise embodiment of the invention herein disclosed, may be made within the scope of what is claimed, without departing 30 from the spirit of the invention.

Referring to the drawing:

Figure 1 is a front elevational view of a house number plate constructed in accordance with the invention.

35 Figure 2 is a sectional view taken on line 2-2 of Figure 1.

Figure 3 is a sectional view taken on line 3-3 of Figure 1.

40 Figure 4 is a sectional view taken on line 4-4 of Figure 1.

Referring to the drawing in detail, the device includes a main supporting plate 5 which is formed preferably of a length of sheet metal having a plurality of rectangular openings 45 6 formed therein, the side edges of the openings being bent inwardly defining flanges 7.

The upper and lower edges of the openings 6 are spaced from the upper and lower edges of the main or supporting plate so that the 50 ends of the number plates 7', which are positioned over the flanges, will overlap the under surface of the main or supporting plate 5, to insure against the number plates sliding from their positions.

55 These number plates are also formed of

sheet metal material and have numbers stamped therefrom defining openings outlining numbers so that when light rays are projected therethrough, the numbers will be clearly visible. Thus it will be seen that due 60 to this construction the number plates 7' may be readily and easily removed and replaced at the will of the user.

The upper edge of the plate 5 is bent rearwardly in spaced relation with the main portion of the plate 5 defining an elongated space to receive the upper edge of the strip of flexible celluloid 8 which is frosted to permit light rays to pass therethrough but prevent 65 glaring of the numbers.

70 The side edges of the plate 5 are also turned inwardly defining vertical flanges at the ends of the main plate 5 to receive the ends of the main plate 5 to receive the ends of the flexible celluloid strip 8. The lower edge of 75 the plate 5 is extended inwardly into close engagement with the rear surface of the plate 5, portions thereof between adjacent flanges 7, being extended outwardly defining lips 9 under which portions of the lower edge of the 80 celluloid strip 8, are positioned.

It will be obvious that the celluloid strip will be securely held to the rear surface of the supporting plate 5, eliminating any possibility of the celluloid strip becoming displaced, but at the same time allowing the strip to be readily and easily removed.

I claim:

A number plate including a body portion 90 formed of a length of sheet metal, inwardly extended flanges formed along the upper and lower edges thereof, inwardly extended flanges formed along the ends of the body portion, said body portion being formed with openings defining spacing bars, the edges of 95 the openings extending inwardly defining flanges, number plates having cut out portions defining numbers, said number plates having their upper edges curved rearwardly and overlying the flanges, a translucent member positioned at the rear of the number plates and contacting with the outwardly curved edges of the number plates and the upper and lower edges of the translucent member being positioned under the inwardly 100 extended flange to secure the translucent member and number plates in position.

105 In testimony that I claim the foregoing as my own, I have hereto affixed my signature.

GEORGE C. ZELLER.
